UNITED STATES PATENT OFFICE.

ELMER HASLETT, OF SAN FRANCISCO, CALIFORNIA.

BIDET.

Application filed May 11, 1926. Serial No. 108,420.

This invention relates to bidets and has for an object to provide an improved bidet which may be quickly and easily attached to and detached from standard water closet or toilet seats upon which it may be supported, without the use of tools; with which its contents may be drained into the bowl of the toilet upon the seat of which it may be supported, without removing the bidet from the seat; and which when not in use may be collapsed into a relatively small, compact and conveniently handled and stored article.

A further object of the invention is to provide an improved bidet of this type which will be sanitary and relatively simple and inexpensive.

Various other objects and advantages will appear from the following description of an embodiment of the invention, and the novel features will be particularly pointed out in the appended claims.

In the accompanying drawings:

Figure 1 is a sectional elevation of part of a toilet having attached thereto a bidet constructed in accordance with the invention;

Figure 2 is a plan of the same;

Figure 3 is a sectional elevation similar to Figure 1 but with the bidet arranged to drain its contents.

Figure 4 is a sectional elevation somewhat similar to Figure 1, of a portion of a toilet having attached thereto a bidet also constructed in accordance with the invention, but illustrating another embodiment of the invention;

Figure 5 is a plan of the same;

Figure 6 is a sectional elevation as in Figure 4, but with the bidet basin filled with a liquid ready for use; and

Figure 7 is a view corresponding to Figure 6, but with the seat of the toilet partially raised to illustrate the manner of draining the liquid from the bidet basin into the toilet bowl after use of the toilet.

In the embodiment of the invention illustrated in Figures 1 to 3 an improved bidet is attached to the usual seat ring 2 of the ordinary toilet seat which is supported above the usual bowl 3, the ring being hinged to the bowl top by the usual arms 2^a connected to the pintle 2^b. The bidet is formed of a basin section 4 depending into the bowl 3,

and having a flange 5 extending peripherally along its open edge, and overlying the seat ring 2 by which it is supported. The basin section 4 is provided along its rear end with a laterally extending or elongated slit or aperture 6 in its bottom wall, through which its contents may be drained into the bowl of the closet.

A partition wall 7 of flexible waterproof material is secured to the bottom and side walls of the basin section immediately in front of the aperture or slit 6, and is considerably wider than the width of the basin section across which it is connected, so that when it is upstanding, as shown in Figures 1 and 2 it will be slightly folded along vertical or upstanding folds. When the partition wall is upstanding, as in Figures 1 and 2, it lies against the rear end wall of the basin section and closes the latter. When dropped down through the slit or aperture 6, as shown in Figure 3, it uncovers the slit or aperture 6 and permits drainage of the basin contents into the toilet or closet bowl. The central part of the partition wall is elongated as a tongue 8 which extends over the flange 5 so as to be supported therefrom when the partition wall is upstanding to close the basin section.

The improved bidet, in its broadest aspects, may be formed of any suitable material, but preferably the basin section, at least, is of flexible, waterproof material. The entire bidet is also preferably formed of a one piece, molded, flexible, resilient rubber, and the flange 5 may then have a turned over or hooked edge 9 which may be snapped over the periphery of the closet or toilet seat ring 2 upon stretching the flange 5 slightly so as to enlarge its dimensions. The engagement of the hooked edge 9 with the ring of the seat serves as an effective means of attachment to the seat. In such a case the tongue 8 may be made of a length sufficient to extend over the rear end of the seat ring 2 and flange 5, and be hooked under the hooked edge 9 at the rear, as shown in Figures 1 and 2. Then when the flange 5 is snapped over the seat ring after the tongue has first been turned under the flange 9 and attached first at the rear of the seat, the tongue 8 will be frictionally anchored and will hold the partition wall upstanding. The tongue 8 may be pulled

out and inserted through the slit 6 when the basin contents are to be drained into the closet bowl, this position of the parts being shown in Figure 3.

5 Such a bidet when not in use may be folded into a small and compact bundle or article. To put it upon the seat of a water closet or toilet, the tongue 8 is first folded under or around the flange 5 at the rear, 10 that is, under the hook 9 of the flange 5, and both tongue 8 and the rear end of the flange 5 hooked over the rear end of the seat ring. The flange 5 is then stretched and snapped over the seat ring all of the way around, as 15 shown in Figures 1 and 2, so that the bidet entirely covers and adheres to the seat. Water or other liquid may then be placed in the basin section. A person using the bidet may sit upon it, preferably facing 20 the rear because the seats are usually wider at the rear which gives more room for the hands in performing the usual operation.

At the conclusion of the operation, the tongue 8 may be pulled out from under the 25 hook 9 of the flange 5, and passed through the slit 6 as shown in Figure 3, allowing passage of the basin section contents into the bowl of the toilet. The bidet may then be flushed out, wiped dry with a towel, removed from the seat, folded and stored 30 away.

In Figures 4 to 7 another embodiment of the invention is illustrated, in which the parts of the usual toilet or water closet are 35 designated by the same reference numerals as in Figures 1 to 3. In the embodiment of the invention, the basin section 10 of the bidet is suspended within the bowl 3 of the toilet by its circumferentially extending flange 11. 40 The flange 11 terminates at its free edge in a hook portion 12 which is adapted to snap over the outer circumferential edge of the seat ring 2 when the flange 11 is stretched outwardly and forwardly somewhat, after its 45 rear edge has first been hooked over the rear edge of the seat ring, as explained in connection with the embodiment of Figures 1 to 3.

Instead of the slit 6 and the partition 50 wall 7 of Figures 1 to 3, the basin section 10 is provided in its rear end wall with a horizontally elongated opening 13 discharging into relatively flat tubular rearward extension 14. The opening 13 is located in the 55 rear wall of the basin section 10 at a point several inches above the bottom wall, and the tubular extension depends into the bowl of the toilet.

In the use of the embodiment of the invention shown in Figures 4 to 7, the flange 60 11 is attached to the toilet seat by stretching it and snapping its hooked edge 12 thereover, as explained, with the basin depending into the toilet bowl as shown in Figure 4. 65 The basin section is then filled to the de-

sired extent below the level of the opening 13, as shown in Figure 6. The bidet may then be used in the usual manner, and then the seat may be raised slowly to the position shown in Figure 7 and then higher, so as 70 to allow drainage of the liquid in the bidet basin through the opening 13 and the tubular extension 14 into the toilet bowl.

The seat may again be lowered, the basin section flushed with clean water and the seat 75 slowly elevated to discharge the flush water. The bidet may then be wiped dry or allowed to dry and then removed and stored.

Such an embodiment of the bidet is also preferably made of molded flexible resilient rubber, particularly the flange portion, and is easily collapsed into a flat compact bundle for storage.

It will be obvious that various changes in the details and materials, which have been herein described and illustrated in order to explain the nature of the invention, may be made by those skilled in the art within the principle and scope of the invention.

Claims:

1. A portable bidet for toilets having a seat portion and a bowl portion, comprising a basin of a size and shape to depend into said bowl portion and be spaced from the walls and contents thereof, and a flange extending outwardly from the open edge of said basin to rest upon and be supported by said seat portion and terminating at its free edge in a hooked stretchable resilient portion to snap over the outer edge of said seat portion and secure the flange and basin against movement upon said seat portion, with the basin suspended in said bowl portion and out of contact with the walls and contents of the bowl portion, said basin having a drain by which its contents may at will be discharged into the toilet bowl while the basin is supported by the seat.

2. A portable device for attachment to toilets of the type having a seat portion with an underneath bowl portion, comprising a basin of a size to depend into the bowl portion and be spaced from the walls and contents of the bowl portion, said basin having an extension portion engageable with and hookable over the seat portion of the toilet surrounding the bowl so as to be suspended therefrom and be held thereby against sidewise movement thereon, said basin and extension being formed of resilient stretchable rubber whereby the device may collapse into a flat condition when removed from the toilet and may stretch and snap over the seat portion when applied thereto, said basin also having a drain by which its contents may be emptied into the bowl portion while the bidet remains attached to the seat portion.

3. A bidet comprising a basin section of a size to depend into the ordinary toilet bowl,

and means for detachably connecting the basin section to the usual seat ring of a toilet so as to be suspended therefrom with the basin section depending into the said bowl, said basin section having a drainage opening adjacent the rear end by which the contents of the basin section may be drained into the toilet bowl without removing the bidet from the seat ring and by merely lifting the seat ring in the usual manner.

4. A bidet comprising a basin section of a size to depend into the ordinary toilet bowl, and means for detachably connecting the basin section to the usual seat ring of a toilet so as to be suspended therefrom with the basin section depending into the said bowl, said basin section having a drainage opening in its rear wall at a level materially above the bottom wall, whereby it may be drained into the bowl by merely lifting the seat ring in the usual manner.

5. A bidet comprising a basin section of a size to depend into the ordinary toilet bowl, and means for detachably connecting the basin section to the usual seat ring of a toilet with the basin section depending into the said bowl, said basin section having at its rear end a tubular extension extending into the bowl of the toilet and opening into the interior of the basin section at a level materially above the bottom wall of the basin section, whereby as the seat ring is raised, the contents of the basin section will drain into the toilet bowl through the tubular extension.

6. A bidet comprising a basin section of a size to depend into the ordinary toilet bowl, and means for detachably connecting the basin section to the usual seat ring of a toilet so as to be suspended therefrom with the basin section depending into the said bowl, said basin section having a drainage opening in its rear wall at a level materially above the bottom wall, said basin section and seat connecting means being formed of flexible rubber so as to collapse into a substantially flat condition when detached from the seat.

7. A bidet comprising a basin section of a size to depend into the ordinary toilet bowl, and means for detachably connecting the basin section to the usual seat ring of a toilet so as to be suspended therefrom with the basin section depending into the said bowl, said basin section having at its rear end a tubular extension extending into the bowl of the toilet and opening into the interior of the basin section at a level materially above the bottom wall of the basin section, whereby as the seat ring is raised, the contents of the basin section will drain into the toilet bowl through the tubular extension, said bidet being formed of flexible rubber so as to collapse into a substantially flat condition when detached from the seat.

8. A bidet comprising a basin section of a size to depend into the ordinary toilet bowl, and means for detachably connecting the basin section to the usual seat ring of a toilet with the basin section depending into the said bowl, said basin section having at its rear end a tubular extension extending into the bowl of the toilet and opening into the interior of the basin section at a level materially above the bottom wall of the basin section, whereby as the seat ring is raised, the contents of the basin section will drain into the toilet bowl through the tubular extension, said bidet being formed of flexible rubber and said connecting means comprising a flange of flexible rubber of a size to stretch and snap over the seat ring.

9. A portable device for attachment to toilets of the type having a seat portion and beneath it a bowl portion, comprising a collapsible basin of flexible water-proof material of a size to depend into and be spaced from said bowl portion, and having resilient extension sections which may be stretched and detachably snapped over the outer edge of the seat portion of the toilet so as to be supported therefrom with the basin suspended in the open face of the bowl portion and out of contact with the walls of the bowl portion and its contents, said basin having a drain by which its contents may be discharged into said bowl portion without its removal from the seat portion.

10. A portable bidet for attachment to the usual water closet toilets having a seat portion above a bowl portion, said bidet comprising a basin materially smaller than said bowl portion, and supporting means extending outwardly and laterally from said basin adjacent its edge at its open face to rest upon and be supported by the upper surface of said seat, said means being detachably engageable with the outer edge of the seat portion to prevent material lateral movement of the basin, said basin having a drain opening by which its contents may be emptied into the bowl portion without removal of the bidet from the seat portion.

11. A portable bidet for attachment to the usual water closet toilets having a seat portion above a bowl portion, said bidet comprising a basin materially smaller than said bowl portion, and supporting means extending outwardly and laterally from said basin adjacent its edge at its open face to rest upon and be supported by the upper surface of said seat, said means being detachably engageable with the outer edge of the seat portion to prevent material lateral movement of the basin, said basin having a drain opening in its rear end wall by which the contents may be emptied into the bowl portion by merely raising the seat portion with the bidet attached thereto.
